UNITED STATES PATENT OFFICE.

HARRIET LYONS REDMOND, OF BOSTON, MASSACHUSETTS, ASSIGNOR TO THE WILLIAM CARTER COMPANY, OF NEEDHAM HEIGHTS, MASSACHUSETTS, A CORPORATION OF MASSACHUSETTS.

INFANT'S BAND.

Application filed May 2, 1922. Serial No. 557,917.

To all whom it may concern:

Be it known that I, HARRIET LYONS REDMOND, a citizen of the United States, and a resident of Boston, in the county of Suffolk and State of Massachusetts, have invented an Improvement in Infants' Bands, of which the following description, in connection with the accompanying drawings, is a specification, like characters on the drawings representing like parts.

This invention relates to infants' undergarments and particularly to infants' bands or shirts, to the lower portion of which a diaper or the like is adapted to be attached.

In order that the principle of the invention may be readily understood I have disclosed a single embodiment thereof in the accompanying drawings, wherein—

Fig. 1 is a plan view of the front of the garment, partially broken away at the lower portion; and

Fig. 2 is a vertical transverse section on the line 2—2 of Fig. 1.

Referring more particularly to the drawings, the band or shirt in its entirety is indicated at 1. The band is preferably of knitted material having the wales 2 extending lengthwise of the band or shirt rather than transversely thereof. This construction renders the band highly elastic in a transverse direction. The band is formed with a trunk or body portion 3 shown as a seamless tubular member, at the upper extremity of which are provided shoulder straps 4 preferably formed integral with the body portion, the wales thereof likewise extending longitudinally of the garment. The upper and lower edges of the body portion and the edges of said shoulder straps are reinforced or protected in any suitable manner as by elastic seaming 5 or other suitable sewing operation. In this manner the edge is of the same degree of elasticity as the body portion of the garment.

The band or shirt 1 is provided with means for attaching a diaper or like member. I am aware that it has been heretofore proposed to provide tabs at the front and rear for a similar purpose, but the structure herein disclosed has been found highly efficient in practical use and possesses certain advantages which I will hereinafter point out.

In order to accomplish this purpose I

have provided a flap-like member 6, clearly seen in Fig. 1 and in section in Fig. 2. Said flap-like member 6 preferably consists of a strip of knitted material such as cotton or other suitable yarn, forming a fabric of suitable texture for receiving and supporting pins or like attaching means, not shown, for a diaper or napkin. Said flap-like member 6 may be knitted as an integral continuous band or as a strip united at its ends to form a continuous member and is preferably formed of a plurality of thicknesses, and herein two thicknesses of knitted material 7 and 8 folded upon themselves at 9 and provided with an elastic seaming or binding 10 similar to the seaming 5 of the body portion of the band. Obviously said flap 6 may be formed of one, or several separate strips of fabric united by seaming at their lower edge.

Said flap-like member 6 is secured to the under face of the body portion of the band 1 near the lower extremity thereof, by an elastic seaming 11 extending transversely about the band and passing through both thicknesses 7 and 8 of the flap member 6 at 12 the upper edge thereof. In this manner the normal or desirable elasticity of the band or shirt is in no way impaired, so that the garment where the flap is secured is substantially as expandable laterally as at any other point. Obviously the reinforcing flap 6 may be attached upon the outer face of the body portion of the garment but the arrangement above described is found preferable. The lower edge 9 of the flap-like member 6 desirably is unattached to the body portion of the garment as is clearly seen in Fig. 2. The reinforcing flap 6 preferably extends downwardly approximately to the lower edge of the body portion of the band 1 but not below it, whereby a pleasing, finished appearance is given to the band.

By the provision of a continuously extending reinforcing member or flap for receiving the pins or other means for attaching the diaper or like member the pull upon the band is distributed more evenly about the entire lower portion thereof. Moreover the diaper attaching means may be fastened to the band at any point about its lower periphery rather than only at the front and rear as has heretofore been the practice so

far as I am aware. The above described construction thus adapts the band for use with any of the various styles of diapers or like members, and to the various methods of attaching the same. Moreover by the provision of a continuous reinforcing member the diaper attaching means such as pins will not wear upon the garment at one or two points only as is the case when small tabs are provided. Said continuous flap may obviously be removed and replaced if worn by pinning of the diaper thereto and also affords additional warmth and protection for the abdomen of the wearer.

Having thus described one illustrative embodiment of my invention, I desire it to be understood that although specific terms are employed they are used in a generic and descriptive sense and without purposes of limitation, the scope of the invention being set forth in the following claims.

Claims—

1. An infant's shirt or band having an undivided tubular elastic body portion and a continuous relatively narrow flap-like

member of substantially the same elasticity as said body portion elastically seamed at its upper edge only upon one face of said body portion at a distance above its lower edge at least equal to the width of said flap-like member, the latter being adapted to receive diaper attaching means at any point or points circumferentially of the band.

2. An infant's shirt or band having a seamless, tubular, knit body portion the lower edge thereof being formed as substantially a straight line transversely of the band, a narrow continuous strip comprising a plurality of thicknesses of knitted fabric secured along the upper edge only thereof upon the inner face of said body portion and terminating short of said straight lower edge of the body portion, said strip being adapted to receive pins or the like for the attachment of a diaper at any point or points circumferentially of the band.

In testimony whereof, I have signed my name to this specification.

HARRIET LYONS REDMOND.
